FIG.1**FIG.2***Fig. 3*

Fig. 4

FIG. 1 is a perspective view of a combined floodlight and support embodying our design, the view from the opposite side being identical;

FIG. 2 is a perspective view of a second embodiment of our new design, the view from the opposite side being identical, and the mast being shown in broken lines for illustrative purposes only;

FIG. 3 is an enlarged side elevational view of the floodlight of each embodiment, the support being omitted for convenience of illustration; and

FIG. 4 is an enlarged top plan view of the floodlight. The flat surface on the front of the floodlight is a window.

This is a division of design application Ser. No. D. 350,-152, filed Apr. 11, 1973.

We claim:

The ornamental design for a combined floodlight and support, substantially as shown and described.
